United States Patent Office.

FRANCIS M. HOLMES, OF BOSTON, MASSACHUSETTS.

Letters Patent No. 105,079, dated July 5, 1870.

IMPROVED FOLDING CHAIR.

The Schedule referred to in these Letters Patent and making part of the same

To all persons to whom these presents may come:

Be it known that I, FRANCIS M. HOLMES, of Boston, in the county of Suffolk and State of Massachusetts, have invented a new and useful Improvement in Folding Chairs; and do hereby declare the same to be fully described in the following specification, reference being had to the accompanying drawing, of which—

Figure 1 is a front elevation;

Figure 2, a side view; and

Figure 3, a vertical section of a folding chair provided with my invention.

In carrying out my present improvement the seat of the chair is to be hinged to a rung or bar firmly fastened to the upper arms of the shorter pair of the curved levers, the said bar, with the two shorter levers and another bar or rung connecting them, composing a rigid frame.

When the seat is pivoted to shorter levers, they are apt to become split or broken by the strain on the points, induced by a person while sitting upon the seat. It is very objectionable, also, to hinge the seat to the tops of the shorter levers.

In this chair the legs and the side bars of the back are formed by four levers, A A' B B'. Each of the shorter levers B B' crosses one of the back or longer levers A A', the two at the crossing being pivoted together or connected by a fulcrum or joint-pin, a, going through one and into the other, or through both, if preferable.

The shorter levers are arranged outside of the longer levers, and are connected by two rungs or cross-bars, b c.

The seat, shown at C, rests on and is hinged as represented at h', directly to the upper rung or bar e; such seat, when the chair is unfolded as exhibited in the drawing, also rests on a round support-bar or rung, e, whose ends are sustained by projections f f extended from the longer levers, in manner as represented.

Furthermore, the two longer levers are connected, near their lower ends, by means of a rung, g, and also at or near their upper ends and middles by two other rungs or bars, h i, fastened to projections k l k l extended from such levers, the whole being arranged in manner as represented in the drawing.

The two rungs, h i, compose part of the back frame, and may be connected by bars or frame-pieces m m.

The seat is furnished with one or more hooks, n, to extend from its rear part, and hook upward around the middle rung i of the longer levers.

From the above it will be seen that, when the seat is horizontal, it will be supported by three rungs, and that it has no direct pivotal connection with either of the levers, it being hinged to the front one of the said three rungs.

I claim—

A folding-chair, as made with its seat C hinged to a rung, e, rigidly fastened to the two shorter levers B B', and as having two other seat-supporting rungs, e i, arranged and applied to the longer levers, as described.

F. M. HOLMES.
